UNITED STATES PATENT OFFICE.

WILLIAM J. BRADLEY, OF TROY, NEW YORK, ASSIGNOR TO THE RAIL JOINT COMPANY, OF NEW YORK, N. Y., A CORPORATION OF NEW YORK.

PROCESS FOR ROLLING TIE-PLATES.

1,197,902.

Specification of Letters Patent. Patented Sept. 12, 1916.

Application filed March 20, 1915. Serial No. 15,790.

To all whom it may concern:

Be it known that I, WILLIAM J. BRADLEY, a citizen of the United States, residing at Troy, in the county of Rensselaer and State 5 of New York, have invented certain new and useful Improvements in Processes for Rolling Tie-Plates, of which the following is a specification.

This invention relates to the manufacture 10 of railway tie-plates, and more particularly to the making of a special design of tie-plate combining the functions of a rail seat and an anti-creeper to prevent longitudinal creeping of the rail.

15 To this end, the invention contemplates a novel process for making this special design of anti-creeper tie-plate in the passes of a rolling mill, whereby the device can be manufactured in an economical and commercial manner, similar to the method employed in rolling rail joint bars from the billet and shearing the finished section into lengths for use.

20 A further object of the invention is to provide a thoroughly practical way for obviating the difficulties which would ordinarily be met in making the special design of tie-plate referred to, while at the same time making the process entirely commercial by the employment of means whereby the 25 rolled tie-plate may be readily adapted for different widths of rail base flanges.

30 With these and many other objects in view which will appear to those familiar with the rolling mill art, the invention consists in the novel process steps hereinafter more fully described, illustrated, and claimed.

35 The essential features of the invention are necessarily susceptible of modification to a reasonable extent without departing from the scope of the appended claims, but for the purposes of illustration, the drawings show a preferred method of carrying the invention into effect both as to process and means.

40 In these drawings, Figure 1 is an elevation of a set of rolls in a rolling mill having a series of passes specially designed to carry out the present invention. Fig. 2 is an enlarged view of the portions of the rolls forming the leader and final passes which complete the tie-plate bar, which is subsequently cut up into tie-plate units. Fig. 3 is a plan view and a projected side view of one of the 45 marginal die rings of the roll of the finish-

ing pass to give final form to one marginal portion of the bar. Fig. 4 is a similar view of the correspondingly opposite marginal die ring for the other marginal portion of the bar. Fig. 5 is a side elevation and projected edge view of the intermediate former ring of the finishing roll, showing the individual die units thereof removably interlocked in the peripheral keeper sockets therefor. Fig. 6 is a similar view of the same ring with the die units thereof removed. Fig. 7 is a series of projected views of one of the individual die units of the former ring. Figs. 8 to 12 inclusive are a series of cross sectional views illustrative of 50 the progressive development of the bar as shaped by the various passes. Fig. 13 is a plan view of the finished bar as it leaves the final pass of the series, indicating by dotted lines the line of cut or shear for severing 55 the bar into tie-plate lengths. Fig. 14 is a detail in perspective of the special design of anti-creeper tie-plate which is the rolling mill product made by the present invention.

60 Like reference characters designate corresponding parts throughout the several figures of the drawings.

The improvements claimed herein are of special importance and utility in the manufacture of a special design of railway tie-plate having the additional function of being a part of an anti-creeping device to prevent creeping of the rails. This particular metal shape presents difficult rolling mill problems which are successfully taken care 65 of by the present invention, so for illustrative purposes the said shape is shown in Fig. 75 14 of the drawings.

70 Referring to the structural characteristics of the anti-creeper tie-plate, or metal shape, 75 which it is proposed to make by the process and apparatus of the present invention, it will be observed that the same essentially comprises a rectangular plate body 1 provided at the upper side thereof with a flat 80 rail seating floor 2. At the opposite marginal edge portions of its floor 2, the plate body 1 has formed thereon the raised rib portions 3 and 4 respectively which extend from one end of the body to the other, and 85 are preferably shaped at the upper and outer sides with the compoundly curved or sigmoidal surfaces 5. These raised rib portions 90 3 and 4 present at their inner edges the vertically disposed inside rail flange bearing 95 100 105 110

shoulders 6, and at their central portions are also preferably formed with raised curving and outwardly and downwardly inclining bearing projections 7 which may be utilized as bearing points or abutments for the under side of screw head spikes, if that type of fastening is used for fastening the tie-plate to the tie.

- A feature of the tie plate construction 10 which presents a difficulty that is not overcome by the ordinary rolling mill processes or rolls is that of the central portion of one of the ribs (4) having its shouldered edge deflected outwardly into the form of an approximately V-shaped recess 8, whose separate inclined portions are outwardly convergent. Also, in connection with this detail of the tie-plate, the flat floor of the body thereof has countersunk therein a clearance recess 9 lying immediately adjacent the edge recess 8 and representing an elimination of metal at a point where it is necessary to provide a product having the functional characteristics required thereof.
- 15 This special design of tie-plate or metal shape has its inception in a billet or bar blank which is progressively developed and shaped in a series of passes of a set of mill rolls which are generally designated in the drawings by the reference letters A, B, and C. The metal shape or bar is given its approximately primary form and size in the first pass of the rolls. This pass is designated by the numeral I and the walls there-
- 20 of are formed by roll members having reducing collars 10 provided with circumferential or peripheral grooves 11 which are spaced apart in a manner to effect a reduction of the bar in its middle portion, and
- 25 a displacement of the metal upon both sides thereof into the form of rounded ribs r. This metal shape is shown in Fig. 8 of the drawings, and it will be observed that the rounded ribs r are arranged in pairs at both
- 30 sides of the bar blank, and those at one side of the blank are in directly opposite relation to those at the opposite side of the blank, thereby leaving a substantial and ample body of metal adjacent both of the lateral
- 35 edges of the blank to provide for the full and proper development of the ribs in the completed article. The double ribbed metal shape delivered from the first pass of the rolls is then acted upon by the rolls forming
- 40 the second pass II, which is partly formed by one of the rolls of the first pass and a roll member having an intermediate spreading collar 11^a formed with beveled edges 12, and rounded former rings 13 placed upon
- 45 the roll mandrel at opposite sides of the collar 11^a. The effect of this roll formation at the second pass II is to initiate the rounded external form of the ribs at what may now be termed the upper side of the bar
- 50 blank and also to initiate the proper separa-

tion of these ribs and the inside flat shoulder formation 6. The metal shape at this point in the process has the form shown in Fig. 9 of the drawings, and still has the projecting ribs r at both sides thereof.

The next step in the process is to provide for the final shaping and spacing of the inside flat bearing shoulder 6, and in this operation the necessary additional metal to provide for the full and proper formation of the shouldered ribs at the upper side of the blank is supplied from the body of metal in the ribs at the under side of the blank. During this process of reduction and redistribution of metal, the projecting ribs of 80 metal at the under side of the blank disappear. The said final shaping and spacing of the inside flat bearing shoulders 6 is accomplished in passes III and IV of the rolls. With respect to pass III, it will be 85 noted from Fig. 1 of the drawings that this pass is provided between roll members, one of which has a reducing collar 10^a formed with shallow peripheral grooves 14 of less depth than the preceding grooves 11, and the other of which roll members includes 90 rounded former rings 15, similar to the previous rings 13, and intermediate reducing rings 16 and 17 which further develop the flat floor 2 of the bar blank, and one of 95 which rings, designated by the reference number 17 may be termed a rib-gaging die-ring. This latter ring is readily removable and replaceable and is employed in varying sizes according to the required distance between the inside bearing shoulders 6, which 100 distance is determined by the width of the rail base flange. A further reduction and shaping to determine the distance between the inside shoulders 6 and the final working out of the projecting ribs from the base or under side of the blank are effected in 105 pass IV. This pass is provided between roll members, one of which substantially consists of a plain reducing collar 18 which 110 flattens the base. The other roll member of the pass IV comprises rounded marginal former rings 19, and intermediate reducing rings 20 and 21, the latter like the rings 17 being a rib-gaging die-ring and inter- 115 changeable with other sizes.

The final reduction and shaping of the bar blank occurs in the final pass of the series designated by the reference number V. The latter pass is provided between roll 120 members, one of which substantially consists of a plain reducing collar 22 which maintains the flat formation of the base or under side of the blank. The other roll member for this final pass embodies important and practical features of construction because of the difficulty involved in rolling into form the final details of the tie-plate blank. The structural elements of this other roll member for the final pass are plainly 125 130

shown in Figs. 2 to 7 inclusive of the drawings. The said roll member essentially includes in its general organization, one or more intermediate plain reducing collars 23 whose peripheries are perfectly flat and smooth to maintain the flat formation for the floor 2 of the tie-plate blank. In addition thereto the said roll member includes a pair of opposite marginal die-rings 24 and 25 of substantially duplicate construction, though usually being of a different width to adapt them respectively to the different widths and slightly differing locations of the opposite raised rib portions 3 and 4 of the tie-plate blank. Referring more particularly to these marginal die-rings 24 and 25, it is to be noted that the same are formed with compoundly curved or sigmoidal surfaces which give a final reduction and shape to the corresponding surfaces 5 of the said rib portions 3 and 4. Furthermore, the said rings 24 and 25 are provided about their peripheries with a continuous alternation of die recesses 26 and die projections 27 and 28 respectively, so that as the said rings roll upon the marginal edges of the bar blank, the same will not only give final form and size to the ribs 3 and 4, but will also develop and shape the raised bearing projections 7 on the said ribs.

One of the distinctive features of the invention, with respect to the apparatus is that of the intermediate forming ring 29 which constitutes one of the active elements of the sectional roll member made up of the rings 17^b, 23, 24, and 25. The intermediate forming ring is provided in its periphery with a plurality of dove-tailed or equivalent shaped keeper sockets 30 adapted to have interlocked therewith the correspondingly shaped holding tongues 31 forming a part of the individual die units 32 which are carried by the rings. The said forming ring 29 is clamped in place between one of the collars 23 and the marginal die ring 25, thereby being well and strongly backed by the collar 23, which is a necessary feature because of the lateral strain imposed upon the said forming ring in performing its work in the final pass.

The individual die units 32 are specially designed to perform the double function of shaping the V-shaped edge recess 8 in the rib 4 of the tie-plate blank, and also the countersunk recess 9 in the floor of the blank. Accordingly, each of said units 32 is provided with a flat outer end having a sufficient projection beyond the adjacent collar 23 to displace metal from the floor 60 of the blank and produce the said recess 9, and is also provided upon one side thereof with a projecting substantially V-shaped or angular die face 33 which impresses itself into the metal of the inside edge of the rib 4 and displaces the same in directions that

will leave the reentrant approximately V-shaped recess 8 which is a required detail of the finished product, so that the latter may perform its anti-creeper functions. In connection with this special design sectional 70 lower member for the final pass, it will be readily understood from the foregoing that breakages of roll parts are practically limited to the individual die-units 32 which are readily removed and replaced with little 75 expense. At the same time the construction described provides for an economic and practical distribution of metal so that the required weight and strength of tie-plates may be successfully manufactured. 80

As clearly shown in Fig. 13 of the drawings, the bar blank as it leaves the final pass of the rolls is formed with a succession of tie-plate units, and these units are separated or cut off from the blank by a shear or other means as indicated by the dotted lines X—X in Fig. 13. Punchings for fastening spikes may be made in the bar blank or in the individual units cut off therefrom as preferred or desirable. 85

From the foregoing it is thought that the essential features of the invention both as to process and apparatus will be readily apparent without further description, and it will be understood that any changes, within the scope of the appended claims, may be resorted to without departing from the spirit of the invention or sacrificing any of the advantages thereof. 90

I claim:

1. A process for rolling tie-plate bars which consists in passing the bar blank through a roll pass to produce a shape having projections of metal upon both sides and adjacent both lateral edges thereof, the 105 projections on one face of the blank being directly opposite those on the other face of the blank, and subsequently subjecting the blank to a series of passes which redistribute the metal from all of said projections into a 110 single pair of ribs at one side only of the bar.

2. A process of rolling tie-plate bars which consists in passing a bar blank through a roll pass to produce a shape having projections of metal upon both sides thereof and adjacent both lateral edges, and subsequently subjecting said shape to a series of passes which redistribute the metal into a single pair of shouldered ribs upon 115 one side only of the bar. 120

3. A process of rolling tie-plate bars which consists in passing a bar blank through a roll pass to produce a shape having directly opposite projections of metal 125 upon both sides thereof and adjacent both lateral edges, then subjecting the said shape to other passes which redistribute the metal to obliterate the projections on one side and to form a single pair of shouldered ribs 130 135

upon the other side of the shape, and finally subjecting the blank to a pass which displaces the metal from the inner side of one of the ribs forming a recess therein.

- 5 4. A process of rolling tie-plate bars which consists in passing a bar blank through a roll pass to produce a shape having directly opposite projections of metal upon both sides thereof and adjacent both lateral edges, then subjecting the said shape to other passes which redistribute the metal to obliterate the projections on one side and to form a single pair of shouldered ribs upon the other side of the shape, and finally subjecting the blank to a pass which displaces the metal from the inner side of one of the ribs forming a recess therein and also which displaces metal from the upper side of the blank adjacent the said recess.
- 10 15 5. A process of rolling tie-plate bars

which consists in passing a bar blank through a roll pass to form a shape having directly opposite projections of metal at both sides and adjacent both lateral edges thereof, then subjecting the blank to other 25 passes which redistribute the metal from said projections into a single pair of ribs projecting from one side of the blank only, subsequently displacing metal from the floor of the blank adjacent one of the ribs forming 30 a counter-sink, and finally shearing the bar blank at points between the counter-sinks.

In testimony whereof I hereunto affix my signature in the presence of two witnesses. 35
